METALLIC FILM ADJUSTABLE RESISTOR AND CONTACT BRUSH THEREFOR

Ora F. Kuhlman, Manhattan Beach, Calif., assignor to Servomechanisms, Inc., a corporation of New York

Application November 4, 1954, Serial No. 466,805

11 Claims. (Cl. 201—55)

This invention relates to metallic film adjustable resistors and contact brushes therefor and, more particularly, to such resistors of the type in which the contact brush bears directly on the resistance film.

Adjustable resistors comprising extremely thin films of stable non-oxidising metals thermally evaporated in a vacuum upon an insulation form, such as a glass plate, have been found useful in applications requiring precisely predetermined resistance-displacement characteristics and stability over a wide range of ambient conditions and over a long life cycle. Because of the extreme thinness of the metal films of such resistors, often of a thickness of only a few molecules, it has heretofore been considered impractical to utilize a contact brush or element bearing directly on the film, since the wear of the film by such contact element, while microscopic, may nevertheless be an appreciable fraction of film thickness, thus substantially changing the resistance characteristics of the unit with use. To avoid such an effect, it has heretofore been proposed that the thin resistance film be superposed upon a commutator structure and that contact be made with portions of the commutator elements extending beyond the resistance film. Resistors of such a construction are described and claimed in the patent of David W. Moore, Jr., Reissue No. 23,219, now abandoned, and in the copending application of David W. Moore, Jr., Serial No. 151,430, filed March 23, 1950, now Patent No. 2,720,512.

While the adjustable film resistors described in the aforesaid patent and patent application are entirely satisfactory for many applications, they have certain limitations. For example, they are relatively costly to fabricate and they have a finite resolution limited by the spacing of the commutator elements. The present invention represents an improvement on the resistors described in the aforesaid patent and patent application which overcomes their foregoing limitations.

It is an object of the present invention, therefore, to provide a new and improved metallic film adjustable resistor of relatively simple and inexpensive construction.

It is another object of the invention to provide a new and improved metallic film adjustable resistor having substantially infinite resolution.

It is a further object of the invention to provide a new and improved metallic film adjustable resistor having one or more of the following advantages: a long life cycle, minimum contact noise, and maximum current-carrying capacity and power rating.

It is another object of the invention to provide a new and improved contact brush for use in metallic film adjustable resistors of the type described and contributing to aforesaid advantageous characteristics.

For a better understanding of the present invention, together with other and further objects thereof, reference is had to the following description taken in connection with the accompanying drawing, while its scope will be pointed out in the appended claims.

In accordance with the invention, there is provided a

2

metallic film adjustable resistor comprising a form of insulation material having a plane surface, an elongated strip of thin metallic film formed directly on and bonded to said plane surface, and a contact brush formed of a flat slab of graphite having a body portion and tapered edge portion terminating in a substantially line-contact edge, such body portion having a low-resistance metallic coating. The resistor also includes an adjustable holder for moving such brush along the film strip and holding it in a plane substantially normal to the plane surface and to the tangent of the mean path of movement.

Further in accordance with the invention, there is provided in a metallic film adjustable resistor, a contact brush comprising a flat slab of graphite having a body portion and a tapered edge portion terminating in a substantially line-contact edge, the body portion having a low-resistance metallic coating and the edge portion being uncoated and impregnated with a hardening non-conductive sealing substance.

Referring now to the drawing, the single figure is a perspective view of a metallic film adjustable resistor embodying the invention and incorporating a contact brush embodying a feature of the invention.

In the drawing there is illustrated a metallic film adjustable resistor comprising a form of insulation material, such as a circular disc 10 of glass or ceramic having an accurately plane upper surface 10a. On the surface 10a is formed an elongated arcuate resistance strip of thin metallic film 11 having low-resistance terminal coatings 11a, 11b for external connections. The film 11 may be of a noble metal, a nickel-chromium alloy, or other stable substantially non-oxidising metal or metallic alloy. It is preferably formed directly on the surface 10a by thermal evaporation in a vacuum, as well understood in the art, so that it is firmly bonded to the surface 10a. Alternatively, the resistor element 10, 11 may be of the type described and claimed in the copending application of Moore and Kuhlman, Serial No. 466,806, filed concurrently herewith.

The resistor of the invention also includes a contact brush 12 in the form of a flat slab of graphite having a body portion 12a and a contact edge portion 12b which may be tapered, as shown, terminating in a substantially line-contact edge 12c. For supporting the brush 12, there is provided an adjustable radially extending holder 13 extending from a hub 14 pivoted on a shaft 15. The brush holder 13 is thus effective to move the brush 12 along the film strip 11, while holding it in a plane substantially normal to the plane surface 10a and also substantially normal to the tangent 16 of its mean arcuate path of movement 17 which coincides with the center of the film strip 11. In other words, the brush 12 is at all times maintained substantially radial to the film strip 11.

The brush holder 13, 14 includes spring means for biasing the brush 12 vertically into contact with the film strip 11, while restricting brush movement to a vertical plane. This spring means may be in the form of a wire or leaf spring 18 secured to the hub 14 and engaging a hole 12d in the brush element, the spring 18 being under stress to bias the brush 12 vertically downward into engagement with the film strip 11. The spring means includes a second wire or leaf spring 19 secured to the hub 14 and engaging the face of brush 12 opposite the holder 13 and stressed to maintain the brush 12 in close contact with the brush holder 13. The elements for mounting the brush 12 thus support it for an articulated motion; that is, the brush can rock or move in a vertical plane to accommodate any irregularities in the plane surface of the disc, while the spring 19 restricts its movement to the vertical plane determined by the vertical face of the holder 13.

The contact brush 12 is preferably graphite of an

electrographitic grade having a Shore scleroscope hardness in the range 20-45 and having a specific resistance in the range of 0.0004 to 0.002 ohm per inch cube. In fabricating the brush 12, the lower edge portion 12b, which may be flat or tapered, as shown, is coated with a commercial photographic resist, for example, asphaltum dissolved in turpentine or xylene. The brush element 12 is then provided with a low-resistance metallic coating, for example, a flash copper coating and a superposed electroplated silver coating of a thickness of the order of 0.001 inch. After coating the surface of brush 12 other than that covered with the resist, it is immersed in a solvent to remove the resist and the remaining solvent is then allowed to dry.

The commercial resist obviously keeps the edge portion 12b uncoated and this uncoated portion is then preferably vacuum impregnated with a liquid capable of hardening into a homogeneous non-conductive sealing and bonding substance. This vacuum impregnation may be carried out in a conventional manner, for example, the brush 12 may be supported in a vacuum bell jar and degassed. Thereafter, by external control means, the brush is lowered so that the uncoated edge portion 12b is lowered into a container of sealing compound. The sealing compound is not critical, but it has been found that almost any liquid material hardening into a non-conductive homogeneous mass which will be stable under the environmental conditions of the final resistor as a whole is satisfactory. Specifically, it has been found that satisfactory sealing is provided by the following mixture:

Parts by weight	
Water white grade rosin	1
Castor oil	2
N-amyl alcohol	7

With such an impregnated graphite brush it has been found that, in the initial usage of the resistor, the brush forms on the film strip 11 a light deposit of the graphite and sealing compound mixture which fills in microscopic irregularities of the surface of the film strip 11, reducing the contact noise level to a minimum after a short breaking-in period. However, this deposit of the graphite and sealing compound mixture during the breaking-in period does not materially affect the total resistance of the film strip 11. The effect of the impregnation of the edge portion 12b of the brush 12 is thought to be primarily that of a lubricant for the abrasive graphite particles, particularly when the resulting resistor is to be used at an unusually dry high altitude.

While the dimensions of the adjustable metallic film resistor and its contact brush are not critical but may be proportioned in accordance with the desired characteristics, one satisfactory contact brush has been in the form of a slab of graphite having a hardness of 35 and a specific resistance of 0.0004 ohm per inch cube, 0.010" thick, 0.125" high, and 0.093" long, the length being preferably slightly greater than the width of the metallic film strip 11. The uncoated edge portion 12b has a width of 0.03". The constant of the spring 18 was such as to develop a brush pressure of 30 to 40 grams.

It has been found that a metallic film adjustable resistor of the type described has a number of distinct advantages, among which may be mentioned an unusually long life cycle; a high current-carrying and power dissipating rating; an extremely low contact noise and contact resistance; and satisfactory operation in dry, low-pressure, high-altitude atmospheres.

While there has been described what is at present considered to be the preferred embodiment of the invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A metallic film adjustable resistor comprising a form of insulation material having a plane surface; an elongated strip of thin metallic film formed directly on and bonded to said plane surface; a contact brush formed of a flat slab of graphite having a body portion and a tapered edge portion terminating in a substantially line-contact edge, said body portion having a low-resistance metallic coating; and an adjustable holder for moving said brush along said film strip and holding it in a plane substantially normal to said plane surface and to the tangent of the mean path of movement.

2. A metallic film adjustable resistor comprising a circular disc of insulation material having a plane surface; an elongated arcuate strip of thin metallic film formed directly on and bonded to said plane surface; a contact brush formed of a flat slab of graphite having a body portion and a tapered edge portion terminating in a substantially line-contact edge, said body portion having a low-resistance metallic coating; and an adjustable radially extending holder for moving said brush along said film strip and holding it in a plane substantially normal to said plane surface and substantially radial to said film strip.

3. A metallic film adjustable resistor comprising a form of insulation material having a plane surface; an elongated strip of thin metallic film formed directly on and bonded to said plane surface; a contact brush formed of a flat slab of graphite having a body portion and a tapered edge portion terminating in a substantially line-contact edge, said body portion having a low-resistance metallic coating; and an adjustable holder for moving said brush along said film strip and holding it in a plane substantially normal to said plane surface and to the tangent of the mean path of movement, said holder including spring means for biasing said brush into vertical contact with said film strip and restricting brush movement to the vertical plane.

4. In a metallic film adjustable resistor, a contact brush comprising a flat slab of graphite having a body portion and a tapered edge portion terminating in a substantially line-contact edge, said body portion having a low-resistance metallic coating and said edge portion being uncoated and impregnated with a hardening non-conductive sealing substance.

5. In a metallic film adjustable resistor, a contact brush comprising a flat slab of graphite of electrographite grade having a Shore scleroscope hardness in the range of 20 to 45 and having a body portion and a tapered edge portion terminating in a substantially line-contact edge, said body portion having a low-resistance metallic coating and said edge portion being uncoated and impregnated with a hardening non-conductive sealing substance.

6. In a metallic film adjustable resistor, a contact brush comprising a flat slab of graphite having a specific resistance in the range of 0.0004 to 0.002 ohm per inch cube and having a body portion and a tapered edge portion terminating in a substantially line-contact edge, said body portion having a low-resistance metallic coating and said edge portion being uncoated and impregnated with a hardening non-conductive sealing substance.

7. In a metallic film adjustable resistor, a contact brush comprising a flat slab of graphite having a specific resistance of 0.0004 ohm per inch cube and a Shore scleroscope hardness of 35 and having a body portion and a tapered edge portion terminating in a substantially line-contact edge, said body portion having a low-resistance metallic coating and said edge portion being uncoated and impregnated with a hardening non-conductive sealing substance.

8. In a metallic film adjustable resistor, a contact brush comprising a flat slab of graphite having a body portion and a tapered edge portion terminating in a substantially line-contact edge, said body portion having a flashed copper coating and a superposed silver coating and said

edge portion being uncoated and impregnated with a hardening non-conductive sealing substance.

9. In a metallic film adjustable resistor, a contact brush comprising a flat slab of graphite having a body portion and a tapered edge portion terminating in a substantially line-contact edge, said body portion having a low-resistance metallic coating and said edge portion being uncoated and vacuum impregnated with a liquid hardening non-conductive sealing substance.

10. In a metallic film adjustable resistor, a contact brush comprising a flat slab of graphite having a body portion and a tapered edge portion terminating in a substantially line-contact edge, said body portion having a low-resistance metallic coating and said edge portion being uncoated and impregnated with a hardening metallic silicate solution.

11. In a metallic film adjustable resistor, a contact brush comprising a flat slab of graphite having a body portion and a tapered edge portion terminating in a substantially line-contact edge, said body portion having a low-resistance metallic coating and said edge portion being uncoated and impregnated with a mixture comprising essentially water white grade rosin 1 part, castor oil 2 parts, and N-amyl alcohol 7 parts.
